UNITED STATES PATENT OFFICE

2,560,201

SHARPENER FOR FLEXIBLE DOUBLE-
EDGED RAZOR BLADES

Thomas F. Williams, Tamaqua, Pa.

Application October 19, 1948, Serial No. 55,402

3 Claims. (Cl. 51—59)

1

My invention relates to sharpeners for razor blades, and more particularly to sharpeners for flexible double-edged razor blades of the type including opposed pairs of cutting edges and end edges. Specifically, the sharpener of the invention relates to means mounting the blade and means reciprocal relative to said mounting means for honing or sharpening the cutting edges of the blade.

With the foregoing in view, an object of my invention is to provide an improved sharpener for flexible double-edged razor blades.

A further object is to provide an improved sharpener of the class described which includes means providing seats for intermediate portions of the end edges of the blade to support the blade for the honing operation aforesaid.

A further object is to provide an improved sharpener of the class described which includes a pair of opposed end members providing said seats, and rigid frame members connecting the end members together and providing mounting means for the honing means aforesaid.

A further object is to provide in a sharpener such as that last described a pair of recesses providing said seats and receiving the intermediate portions of a blade and edges therein upon flexing and straightening of the blade.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is a plan view of the sharpener according to the invention showing a blade mounted thereon;

Figure 2 is a view like Figure 1, but showing the honing portions of the sharpener in the open position to permit the insertion and removal of a blade into or from the device;

Figure 3 is an end elevation of Figure 1;

Figure 4 is a transverse vertical sectional view taken substantially on the plane of the line 4—4 of Figure 1, but on a slightly larger scale;

Figure 5 is a fragmentary cross-sectional view on a still larger scale and taken substantially on the plane of the line 5—5 of Figure 4;

Figure 6 is a longitudinal vertical sectional view taken substantially on the plane of the line 6—6 of Figure 1.

Referring specifically to the drawing, wherein

2

like reference characters have been used throughout the several views to designate like parts, 10 designates an open frame including a pair of opposed end members 11. Each of the end members is formed with an inwardly-directed seat 12 of a recessed character which is adapted to seat the end lips 13 of a conventional flexible double-edged safety razor blade 14. The seats 12 are spaced apart a distance at least equal to the over-all length of the blade 14. Thus, to insert the blade 14 in the frame 10, it is necessary to first insert one lip 13 in one seat 12 and thereafter slightly flex the blade to reduce the length thereof and insert the opposite lip 13 in the opposite recess or seat 12. Thereafter, the blade 14 is allowed to straighten out and is supported in the seats 12 between the end members 11. In this connection, it is noted that the usual double cutting edges 15 terminate inwardly of the end members 11 for a purpose which will be apparent later.

The end members 11 are connected together in rigidly-spaced relation by at least one side member 16, whereby to provide an open rectangular frame. In the embodiment illustrated, a second side member 17 connects opposite ends of the end members 11 to increase the rigidity of the frame. Likewise, as clearly shown in Figure 4, the side members 16 and 17 are of cylindrical configuration to slidably and rotatably mount the hones thereon now to be described.

Thus, each hone includes a tubular slide 18 which is slidable and pivotal on one of the side members 16 or 17. Likewise, each hone includes 35 a body portion 19 of concave configuration which is rigidly connected to the slide 18. The structure is such that one concave honing surface 19 is adapted to simultaneously engage one side of both cutting edges, while the other concave surface is adapted to simultaneously engage both opposite side edges of the cutting edges 15. As best seen in Figures 2 and 5, each honing surface at the end edges thereof is formed with alternate projections and recesses 20 and 21, respectively, which are staggered so as to interfit in use, whereby to permit a close honing fit with the cutting edges 15 as the surfaces 19 are moved toward each other. Likewise, the interengagement provides a wear take-up means.

50 In use, the hones are swung to the open position illustrated in Figure 2 and partially illustrated in broken lines in Figure 3, and a blade 14 is inserted in the frame 10 as aforesaid. Thereafter, the hones are swung to the closed or full line position of Figures 1, 3 and 4, so that the

honing surfaces 19 engage the cutting edges 15 of the blade 14 in a well known manner. Thereafter, the hones are reciprocated relative to the frame 10 until the cutting edges 15 are sufficiently honed. Thereafter, the hones are swung to the open position and the blade 14 is removed as aforesaid.

The particular structure is obviously of small and compact nature, yet strong and sturdy in use, whereby to provide an efficient sharpener for razor blades of the class described. Moreover, while I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

1. In a sharpener for a flexible double edge razor blade, a frame including a pair of spaced end members and a pair of spaced side members arranged intermediate said end members and fixedly secured thereto, means on each of said end members engageable with the adjacent ends of said razor blade for supporting the latter, a first honing member having one end slidably supported on one of said side members and mounted on the latter for swinging movement into engagement with one face of said blade, and a second honing member having one end slidably supported on the other of said side members and mounted on the latter for swinging movement into engagement with the other face of said blade and confronting relation with respect to said first honing member.

2. In a sharpener for a flexible double edge razor blade, a frame including a pair of spaced end members and a pair of spaced side members arranged intermediate said end members and fixedly secured thereto, means on each of said end members engageable with the adjacent ends of said razor blade for supporting the latter, a first honing member having one end slidably supported on one of said side members and mounted on the latter for swinging movement into engagement with one face of said blade, and a second honing member having one end slidably supported on the other of said side members and mounted on the latter for swinging movement into engagement with the other face

of said blade and confronting relation with respect to said first honing member, each of said honing members comprising a body portion having a concaved honing surface adapted to engage the adjacent sides of both cutting edges of said blade when said honing members are in engagement with the faces of said blade.

3. In a sharpener for a flexible double edge razor blade, a frame including a pair of spaced end members and a pair of spaced side members arranged intermediate said end members and fixedly secured thereto, means on each of said end members engageable with the adjacent ends of said razor blade for supporting the latter, a first honing member having one end slidably supported on one of said side members and mounted on the latter for swinging movement into engagement with one face of said blade, a second honing member having one end slidably supported on the other of said side members and mounted on the latter for swinging movement into engagement with the other face of said blade and confronting relation with respect to said first honing member, each of said honing members comprising a body portion having a concaved honing surface adapted to engage the adjacent sides of both cutting edges of said blade when said honing members are in engagement with the faces of said blade, and interengaging means carried on said honing members and engageable with each other upon movement of said honing members into engagement with said blade for effecting a close honing fit with the cutting edges of said blade.
